UNITED STATES PATENT OFFICE

2,490,123

CHANGE-OVER MECHANISM FOR MOVING
PICTURE PROJECTORSCurtis J. Goodman and Aubrey L. West,
Lafayette, Tenn.

Application April 1, 1948, Serial No. 18,396

1 Claim. (Cl. 88—16)

1

Our invention relates to improvements in change-over mechanisms for moving picture projectors, the primary object in view being to provide a simply constructed mechanical change-over for selectively cutting out either of a pair of such projectors, as occasion may require, quickly and easily, by foot pressure.

Another object is to provide mechanism of the character and for the purpose above set forth which is adapted for quick easy installation without altering the projectors and which is not liable to get out of order nor require frequent servicing.

Other and subordinate objects, also within the purview of our invention, together with the precise nature of our improvements will be readily understood when the succeeding description and claims are read with reference to the drawing accompanying and forming part of this specification.

In said drawing:

Figure 1 is a view in front elevation of our improved change-over mechanism, in a preferred embodiment thereof, applied to a pair of moving picture projectors, shown partly in broken lines;

Figure 2 is an inverted perspective view of the actuator drawn to a larger scale;

Figure 3 is a view in longitudinal section of a portion of the actuator taken on a line 3—3 30 of Figure 2, and drawn to a larger scale;

Figure 4 is a detailed view in transverse section taken on the line 4—4 of Figure 3;

Figure 5 is a view in perspective of one of the pedals.

Referring to the drawing by numerals, according to our invention, a pair of side-by-side, moving picture projectors, designated 1, 2 and shown diagrammatically in broken and full lines, as sufficient for the present purposes, are equipped with guides 3, 4 at the apertures 5, 6 thereof and for vertically slideable change-over shutters 7, 8.

Mechanical means are provided for operating the shutters 7, 8, alternately, to cut out either projector 1, 2, and comprising the following.

A pair of foot pedals 9, 10 are provided alongside the outboard sides of the projectors 1, 2, respectively, which are hinged as at 11, 12 to attaching plates, as at 13, secured by screws 14 to the floor 15 of the projection room, not shown, so that said pedals are vertically swingable. Stop screws, as at 16, in said pedals 9, 10 are adjustable for engagement with the floor 15 to limit downward swinging of the pedals 9, 10 as may be required.

2

The pedals 9, 10 are operatively connected to the shutters 7, 8 by means now to be described.

A pair of pull cables 17, 18 are extended upwardly from the pedals 9, 10 over a pair of pulleys 19, 20 suitably fixed to the ceiling 21 of the projection room for connection to an actuator 22 for operating a pair of shutter raising and lowering Bowdin wires 23, 24. The pull cables 17, 18 are connected at lower ends thereof by clamps 25, 26 to short length cables 27, 28 attached, in any suitable manner, to the pedals 9, 10.

The actuator 22 comprising a bar-like bracket 29 secured by screws 30 to the ceiling 21 midway between the projectors 1, 2 and having a pair of depending end bearing ears 31, and a lateral arm 32 projecting downwardly from the center of said bracket, as best shown in Figure 2 and secured to said bracket, as at 33. A horizontal lever 34 is pivoted adjacent one end thereof, as at 35, on said arm 32 to swing from side to side with a pair of upstanding posts 36, 37 on one end thereof to which the upper ends of the pull cables 17, 18 are suitably connected. A shouleder bolt 38 extends upwardly in a longitudinal slot 39 in the other end of the lever 34 to slide along said slot, for a purpose presently clear, and, by means of a nut 40, is fixed in a two-part plate clamp 41, intermediate the ears 31, and secures the parts of said clamp in clamping relation. The clamp 41 at one end thereof is clamped to a slide rod 42 slidably extended at its ends through the ears 31 transversely of the projectors 1, 2, and is adapted to be moved from side to side with the slide rod 42 sliding endwise to exert pull on the Bowdin wires 23, 24 alternately.

The Bowdin wires 23, 24 are suitably connected at lower ends thereof to the shutters 7, 8 to raise and lower the same with lower ends of the sheaths 42, 43 for said wires fixed by clamps 44, 45 to the projectors 1, 2 above the shutters 7, 8 and said wires and sheaths extend upwardly to opposite ends of the bracket 29 of the actuator 22. The upper ends of the sheaths 42, 43 are fixed by snap rings as at 46, in tubular couplings 47, 48 extending oppositely, outwardly, from the ears 31 and threaded into nuts 49, 50 fixed to said ears by welding, not shown. The upper ends of the Bowdin wires 23, 24 extend through said couplings 47, 48 and through openings, as at 49, in said ears and are clamping engaged in end to end relation by the end of the clamp 41 opposite that clamped to the slide rod 42.

In operating the described change-over mechanism, depression of either pedal 9, 10, will,

through corresponding pull cables 17, 18 swing the lever 34 to one or the other side of a central position, for instance, as shown in Figure 1, with pedal 10 depressed. Such swinging of said lever 34 will cause the clamp 40 to move in a corresponding direction to exert a pull on one Bowdin wire, for instance, wire 23, and a push on the other Bowdin wire, for instance, 24, to close the shutter of the projector adjacent the depressed pedal and raise the shutter of the remote projector, thus cutting off the adjacent projector and changing over to the remote one. When one pedal 9, or 10, is depressed, the other is raised for operation. As will be seen, the pull cables 17, 18 and the Bowdin wires may be cut to different lengths as may be required by different spacings of the projectors 1, 2 in a projector room and different heights of ceilings of such rooms.

The foregoing will, it is believed, suffice to impart a clear understanding of our invention, without further explanation.

Manifestly, the invention, as described, is susceptible of modification, without departing from the inventive concept, and right is herein reserved to such modifications as fall within the scope of the appended claim.

Having described the invention what is claimed as new is:

Change-over mechanism for a pair of side-by-side projectors each having an aperture and a

shutter operative to open said aperture, said mechanism comprising an over-head shutter actuator including a fixed bracket, a lever pivotally mounted intermediate its ends on said bracket for swinging in opposite directions, a clamp, a slide rod on said bracket to which said clamp is fixed for movement in opposite directions by sliding of said rod, and sliding pivotal connections between said clamp and one end of said lever whereby movement of the lever in opposite directions correspondingly moves said clamp, a pair of flexible wires with ends gripped by said clamp and ends, connected to said shutters and whereby movement of said clamp in opposite directions operates said shutters to open said apertures alternately, and a pair of pedal operated pull wires connected to the other end of said lever for swinging the same in opposite directions.
